The ornamental design for a well cover head with bark-like exterior, as shown and described.

DESCRIPTION

FIG. 1 is a perspective view of a well cover head with bark-like exterior showing my new design;

FIG. 2 is a front view thereof;

FIG. 3 is a rear view thereof;

FIG. 4 is left side view thereof;

FIG. 5 is a right side view thereof; and,

FIG. 6 is a top view thereof.

The features and broken lines are included for the purpose of showing portions that form no part of the claimed design.
